UNITED STATES PATENT OFFICE.

JOHN T. LANDIS, OF NASHVILLE, TENNESSEE.

PNEUMATIC DILATOR.

1,282,881.

Specification of Letters Patent. Patented Oct. 29, 1918.

Application filed July 7, 1917. Serial No. 179,184.

To all whom it may concern:

Be it known that I, JOHN T. LANDIS, a citizen of the United States, and a resident of Nashville, in the county of Davidson and State of Tennessee, have invented certain new and useful Improvements in Pneumatic Dilators, of which the following is a specification.

My invention is an improvement in pneumatic dilators, and has for its object to provide a dilator of the character specified, for maintaining and restoring the elasticity and pliability of the rectal muscles, when, from indifference and inattention to nature's pro-
15 vision, they have become weakened and pro-
lapsed, and to correct construction.

In the drawings:

Figure 1 is a side view of the invention;

Fig. 2 is a longitudinal section with the
20 valve stem tube and the detachably connected air hose in place;

Fig. 3 is a longitudinal section of the valve stem tube;

Fig. 4 is a longitudinal section of one embodiment of the base;

Fig. 5 is a bottom plan view of the same;

Fig. 6 is a detail section showing the mounting of the nut;

Fig. 7 is a longitudinal section of another
30 embodiment, with the valve stem tube in place;

Fig. 8 is a longitudinal section of the valve stem tube;

Fig. 9 is a transverse section of another embodiment of the base;

Fig. 10 is a longitudinal section of another embodiment of the tube; and

Fig. 11 is a section along the line 11—11 of Fig. 10.

40 In the embodiment of the invention shown in Figs. 1 to 5, the instrument comprises a hollow stem 1 and a hollow head 2, comprising the dilating tube, and a detachable base 3, all of the parts, except the base which is preferably of metal, being of rubber; the stem and head being of soft rubber so that they may be easily pressed into the rectum and expanded, as shown. The dilator tube is detachable, and is intended to be furnished

45 in interchangeable sizes. The head is pointed at the end remote from the stem, as indicated at 2^a, and an annular external shoulder is provided between the head and stem. The lower end of the stem is flaring or funnel

50 shaped as shown at 5, and the inner face of this flaring portion is provided with a nut 6.

This nut has a marginal rib 7 at its upper inner end, which is vulcanized within the annular groove 8, in the flaring portion of the stem, or it may detachably rest on top 60 of the annular inwardly projecting rib or shelf 24, in which latter case the projecting rib coming under the nut's margin and on top of the base is firmly held therebetween by the action of the external threads on the 65 valve stem when the latter is screwed tightly into the nut. The valve stem tube thus serves the purpose of conducting air or other fluids into the dilator stem, and serves also the purpose of connecting the dilator stem 70 to the base.

The base 3, which may or may not be pliable, is provided with a central opening 10, which is encircled on its upper surface by an annular rib 11. The upper portion of the 75 opening is cylindrical to fit about the nut. The end of the nipple or extension bears against the flange 7 and the flaring portion of the opening 10 is designed for a purpose to be described, and at its margin the base 80 has a reinforcing rib 12 on its under face. The flaring portion 5 of the stem fits closely down around the nipple 11 and abuts at its lower end the upper face of the base. The nut, as shown in Fig. 6, is to be vulcanized 85 within the flaring end of the stem. The valve stem tube shown in Figs. 2 and 3 is used to dilate the dilator in connection with a tube for air or other fluid. This valve stem tube has a head 14 at its upper end and 90 has radial openings below the head.

The valve stem tube is of a length to extend through the base to well within the head, and at its lower end it is enlarged and internally threaded, as shown at 16, to receive a valve plunger and the hose connection 17 from a suitable source of fluid under pressure, as from a pump or receptacle.

95 The large portion is externally threaded as indicated at 18, to engage the nut, and at the extremity of the lower end there is provided a radial knurled rib 19 for convenience in turning the valve stem tube into and out of engagement with the nut. Just above the knurled portion of the valve stem tube is a tapered portion fitting within the tapered portion of the opening 10 of the base, and a packing ring or gasket 20 is arranged upon this tapering portion for preventing leakage 100 between the valve stem and nut.

110 In the embodiment of the invention shown in Figs. 7, 8 and 9, the stem 21 of the head

22 is shaped like that of Fig. 2, and in the flaring portion 23 there is provided an annular inwardly projecting rib or shelf 24 on which the nut 25 rests. The peripheral 5 surface of the nut is tapered to fit the flaring portion 23 of the stem, and the base 26 has a central tapering opening 27, the small end of the opening registering with the nut. In this construction the nut is vulcanized on 10 the under side of the rubber inwardly projecting shoulder of the expander tube, and the flaring portion 23 of the stem fits against the base outside of the nut. The valve stem tube 28 is similar to the valve stem tube 15 of Fig. 3, having the annular radial rib 29 and the external threaded portion 30 for engaging the nut. Between the rib and the threaded portion the valve stem tube is conical or tapered as indicated at 31 to fit the 20 opening 27 of the base.

In Figs. 10 and 11 is shown means in connection with the dilator 32 for preventing longitudinal expansion of the dilator. The said means comprises flexible threads 33 25 which extend from one side of the flaring portion of the stem to the other, in the material of the dilator, the full length of the stem and head. These threads may be intermediate the inner and outer surfaces of 30 the dilator, or they may be inlaid externally or internally. In the construction of Fig. 10, a ledge 24^a is provided for receiving the nut shown in Fig. 2.

In operation, the dilator is introduced by 35 inserting the valve stem tube in the dilator, after which the dilator may be inserted in the rectum, the valve stem tube forming a support for such insertion. A hose 17 is connected with the valve stem tube 16, and 40 fluid under pressure is admitted to the dilator, expanding the same. The walls of the rectum may be massaged by expanding the dilator and permitting it to contract. The threads prevent elongation of the 45 dilator, causing the same, in fact, to shorten when it is expanded.

The base of the dilator may be of hard rubber, densely compounded soft rubber, or metal, and the valve stem tube is of metal. 50 The normal size of the dilator, of which there may be different sized interchangeable stems, is such as will permit it to enter without discomfort, and the muscles are gently and evenly expanded without bruising, as in 55 the case of other dilators which effect dilation of the parts by means of the size of the dilator, the size having to be larger than the constricted muscular orifice.

It will be noticed that the base is deep 60 enough to cover the lower end of the valve

stem tube so as to protect it from injury by the wearer when sitting down. The head, when in use, extends above the internal sphincter muscle, and under the air pressure the head swells proportionally with the stem, 65 surrounded as the latter is by the muscles. The head rests upon the upper sphincter muscle and anchors the instrument in place, the base being drawn up snugly by this action against the body. The dilator may be 70 worn while the user attends to his usual duties, thus permitting treatment to be carried on without intermission.

It will be understood that there are three 75 embodiments of the invention shown, namely, that as seen assembled in Fig. 2, wherein the nut is vulcanized in the annular groove 8. This assemblage is made up of the parts shown in Figs. 2, 3, 4 and 6. Second, the construction shown assembled in 80 Fig. 7, wherein the nut is vulcanized to the end portion of an inwardly projecting shoulder, and this embodiment comprises the parts shown in Figs. 7, 8 and 9. Third, the construction comprising the parts shown 85 in Figs. 3, 4 and 10, wherein the nut detachably rests upon the inwardly projecting rib.

I claim:

1. A device of the character specified, 90 comprising a soft flexible elastic stem having at one end a head, a base having a nipple engaging within the stem, a rigid tube for conducting air to the stem and for supporting the same during insertion, and a nut 95 connected with the stem for engagement by the tube, the tube having means for engaging the base to hold it to the stem.

2. A device of the character specified, 100 comprising a soft flexible rubber stem having at one end a head, a base at the other end, a rigid air-conducting tube for supporting the stem during insertion and for supplying air to expand the same, means connected with the stem for engagement by the said tube to hold the same in place, the 105 tube having means for engaging the base to hold it to the stem, the stem and head having threads extending longitudinally thereof and inlaid in the material thereof.

3. A device of the character specified, 110 comprising a soft flexible rubber stem having at one end a head, a base at the other end of the stem, and a rigid air conducting tube for supporting the stem during insertion and for supplying air to expand the 115 same, and means connected with the stem for engagement by the tube to hold the same in place, said tube having means for engaging the base to hold it to the stem.

JOHN T. LANDIS.
